(57) **CLAIM**

The ornamental design for a disposable coffee filter as shown and described.

DESCRIPTION

Figure 1.1 is a first embodiment of a front elevational view of a disposable coffee filter showing my new design;

Figure 1.2 is a back elevational view thereof;

Figure 1.3 is a top plan view thereof;

Figure 1.4 is a bottom view thereof;

Figure 1.5 is a right side view thereof;

Figure 1.6 is a left side view thereof;

Figure 1.7 is an open perspective view thereof.

Figure 2.1 is a second embodiment of a front elevation view of a disposable coffee filter showing my new design;

Figure 2.2 is a back elevational view thereof;

Figure 2.3 is a top plan view thereof;

Figure 2.4 is a bottom view thereof;

Figure 2.5 is a right side view thereof;

Figure 2.6 is a left side view thereof; and

Figure 2.7 is an open perspective view thereof.
